UNITED STATES PATENT OFFICE

HERMAN DEUTSCHMEISTER, OF NEW YORK, N. Y.

PAPER BOX

Application filed August 25, 1928. Serial No. 302,032.

This invention relates to paper boxes. It is directed to a mailing carton for carrying a sample package or bottle and printed matter to advertise the same.

5 Among the objects of this invention is to provide a box of this character formed from a single blank of suitable paper board or like material foldable to form a simple, strong, efficient and practical mailing carton for the 10 purpose described.

Other objects of this invention will in part be obvious and in part hereinafter pointed out.

The invention accordingly consists in the 15 features of construction, combinations of elements, and arrangement of parts which will be exemplified in the construction hereinafter described, and of which the scope of application will be indicated in the following 20 claims.

In the accompanying drawing, in which is shown one of the various possible illustrative embodiments of this invention,

Fig. 1 is a plan view of the unfolded blank 25 from which the box embodying the invention is made;

Fig. 2 is a plan view of the box partly folded;

Fig. 3 is a perspective view of the box with 30 the cover open;

Fig. 4 is a sectional view taken on line 4—4 of Fig. 3, showing a sample package, bottle and printed pamphlet in place within the box; and

35 Fig. 5 is a sectional view taken on line 5—5 of Fig. 3.

Referring in detail to the drawing, 10 designates a single blank from which the box B embodying the invention is made. The blank 40 may be made of any suitable stock paper and comprises a section 11 which constitutes the bottom of the box, a section 12 of the same dimensions as section 11, which constitutes the top of the box, and a section 13 which 45 connects said sections 11, 12 along crease lines 11a, 12a and forms one side of the box. The top section 12 is provided with spaced extensions 14, 15 foldable on crease lines 14a, 15a aligned with the outer edge 16 of said section 12, to form flaps. The bottom section

11 is provided with an extension 17 comprising a section 18 and a section 19. Section 18 forms the side of the box opposite to side 13 and connects section 19 to said section 11 along crease lines 11b, 19b. Said section 19b 55 may be suitably slotted at 20 and 21 to receive the flaps 14 and 15 respectively when said cover is in closed position.

The bottom section 11 is provided with end 60 extensions 20a and 21a, each comprising four contiguous sections designated 22, 23, 24, 25 and 26, 27, 28, 29 respectively. Said extensions 20a and 21a are foldable along crease lines 22a, 23a, 24a, 25a and lines 26a, 27a, 28a, 29a respectively, to form tubular members 30, 65 31 of rectangular cross-section at the ends of said box B, seated on said bottom wall 11 and constituting the end walls of said box. Each of sections 22 and 26 is provided with end flaps 32 foldable along crease lines 33 70 to right angles to said sections to lie against the inner-surface of side walls 13, 18 of the folded box B.

Sections 13, 18, 22 and 26 are preferably of the same height. Section 24 forming the 75 side of tubular member 30 opposite to section 22 is of the same dimension as said section 22. Section 23 forming the top portion of said tubular member 30 may be provided with means for retaining a sample 80 package. Thus said tubular member 30 has a centrally disposed X-shaped slit 34 providing four triangular shaped flaps 35 foldable inwardly along lines 23a, 24a, 36 and 37 to permit a sample package 40 to be inserted 85 into the tubular member 30 thru the top wall 23 thereof. When thus inserted, said package 40 is held in place by said flaps 35 and the top surface 41 thereof is exposed 90 whereby the printing matter or label on said package may be read when the cover 12 of the box B is open.

When extension 20a is folded to form the tubular member 30, section 25 thereof rests 95 on the bottom wall 11 of the box B.

Section 27 forming the top wall of tubular member 31 is preferably of the same dimensions as section 23 to give the box B a symmetrical appearance. Section 28 forming the inner wall of said member 31 is pref- 100

erably of lesser height than section 26, to provide a space between said tubular member and the bottom wall 11 to permit a pamphlet 42 or other printed matter to be inserted in the bottom of the box B. In such position one end of said pamphlet B will abut section 24 of tubular member 30, while the opposite end of said pamphlet will extend underneath tubular member 31.

10 Sections 28 and 29 are preferably formed with a cutout portion 43 providing an opening 43a in section 28. Another article such as a sample bottle 44 may be placed in box B, and the neck portion 45 thereof may extend thru said opening 43a. The base 46 of the bottle may abut section 24 of tubular member 30, which constitutes a support for said bottle.

Section 27 is formed with a slit 50 adjacent one end thereof. Section 19 is formed with a slit 51 providing a flap 52 foldable on crease line 52. Said flap 52 may be inserted in said slit 50 in section 28 to aid in keeping section 19 folded over tubular members 30, 31.

In forming the box B from the blank 10, the extensions 20a, 21a are first folded as described above to form the tubular members 30, 31. The pamphlet 42 may then be placed on section 11, one end of said pamphlet being slipped under tubular member 31. The package 40 and the bottle 44 may then be placed in position as described above. Extension 17 may then be folded, section 19 extending over said tubular members 30, 31, the flap 52 being inserted in slit 50 to maintain said extension 17 in folded position which in turn maintains the extensions 20a, 21a properly folded.

40 Sections 12, 13 may then be folded to close the box B, flaps 14, 15 being inserted in slits 20, 21 to maintain said sections in folded position.

It will thus be seen that there is provided 45 a device in which the several objects of this invention are achieved, and of which is well adapted to meet the conditions of practical use.

As various possible embodiments might 50 be made of the above invention, and as various changes might be made in the embodiment set forth, it is to be understood that all matter herein set forth or shown in the accompanying drawing, is to be interpreted as 55 illustrative and not in a limiting sense.

Having thus described my invention, I claim as new and desire to secure by Letters Patent:—

1. A box made from a one piece blank 60 comprising a bottom wall and opposite upright walls, said upright walls consisting of tubular members of rectangular cross-section, said box being provided with a space between one of said tubular members and 65 said bottom wall to permit insertion of print-

ed matter between said tubular member and said bottom wall.

2. A box made from a one piece blank 70 comprising a bottom wall and opposite upright walls, said upright walls consisting of tubular members of rectangular cross-section, said box being provided with a space between one of said tubular members and said bottom wall to permit insertion of printed matter between said tubular member and said bottom wall, said other tubular member being provided with means for holding a package therein.

3. A box made from a one piece blank 75 comprising a bottom wall and opposite upright walls, said upright walls consisting of tubular members of rectangular cross-section, said box being provided with a space between one of said tubular members and said bottom wall to permit insertion of printed matter between said tubular member and said bottom wall, said other tubular member being provided with an X-shaped split in the top section thereof to permit insertion of a package therein thru said section.

4. A box made from a one piece blank 80 comprising a bottom wall and opposite upright walls, said upright walls consisting of tubular members of rectangular cross-section, one of said tubular members being formed with an opening in the inner side section thereof to permit insertion of a portion of a bottle into said tubular member.

5. A box made from a one piece blank 85 comprising a bottom wall and opposite upright walls, said upright walls consisting of tubular members of rectangular cross-section, one of said tubular members being formed with an opening in the inner side section thereof to permit insertion of a portion of a bottle into said tubular member, said other tubular member being provided with means for supporting a package therein.

6. A box made from a one piece blank 90 comprising a bottom wall and opposite upright walls, said upright walls consisting of tubular members of rectangular cross-section, one of said tubular members being formed with an opening in the inner side section thereof to permit insertion of a portion of a bottle into said tubular member, said other tubular member being provided with a substantially X-shaped slit in the top section thereof to permit insertion of a package therein thru said section.

7. A box made from a one piece blank 95 comprising a bottom wall and opposite upright walls, said upright walls consisting of tubular members of rectangular cross-section, said box being provided with a space between one of said tubular members and said bottom wall to permit insertion of printed matter between said tubular member and said bottom wall, said tubular member being provided with an opening in the inner side section thereof to 100

permit insertion of a portion of a bottle into said member, said other tubular member providing means for supporting the base of said bottle.

- 5 8. A box made from a one piece blank comprising a bottom wall and opposite upright walls, said upright walls consisting of tubular members of rectangular cross-section, one of said tubular members being formed with
10 an opening in the inner side section thereof to permit insertion of a portion of a bottle into said tubular member, said other tubular member being provided with means for supporting a package therein. 70
- 15 9. A box made from a one piece blank comprising a bottom wall and opposite upright walls, said upright walls consisting of tubular members of rectangular cross-section, one of said tubular members being formed with
20 an opening in the inner side section thereof to permit insertion of a portion of a bottle into said tubular member, said other tubular member being provided with means for supporting a package therein, said means comprising a substantially X-shaped slit in the top section thereof. 75
- 25 10. A box made from a one piece blank comprising a bottom wall, end walls consisting of tubular members of rectangular cross-
30 section, and a side wall having an extension foldable over said tubular members, said extension being provided with means adjacent an end thereof for securing said extension to one of said members. 80
- 35 11. A box made from a one piece blank comprising a bottom wall, end walls consisting of tubular members of rectangular cross-
40 section, a side wall having an extension foldable over said tubular members, said extension having means for securing the same to one of said members, and an opposite side wall having an extension foldable over the top of said box to form a closure therefor. 85
- 45 12. A box made from a one piece blank comprising a bottom wall, end walls consisting of tubular members of rectangular cross-
50 section, a side wall having an extension foldable over said tubular members, said extension having means for securing the same to one of said members, and an opposite side wall having an extension foldable over the top of said box to form a closure therefor, said closure extension being provided with means for securing the same in overlapping
55 relation to said first mentioned extension. 90
- 60 13. A case comprising a bottom wall and upright walls, one of said upright walls being tubular and provided with means to permit insertion of a package thru said section. 95
- 65 14. A case comprising a bottom wall and upright walls, one of said upright walls being tubular, a section of said tubular wall being provided with an X-shaped slit to permit insertion of a package thru said section. 100
- 70 15. A box comprising a bottom wall, and 105
- 75
